THE NORRIS PETERS CO., PHOTO-LITHO., WASHINGTON, D. C.

UNITED STATES PATENT OFFICE.

RAY W. SHELDON, OF WHITE CITY, KANSAS.

FIXTURE FOR COMBINATION HAY AND HOG RACKS.

1,143,145.

Specification of Letters Patent. Patented June 15, 1915.

Application filed March 26, 1912. Serial No. 686,839.

To all whom it may concern:

Be it known that I, RAY W. SHELDON, a citizen of the United States, residing at White City, in the county of Morris and 5 State of Kansas, have invented certain new and useful Improvements in Fixtures for Combination Hay and Hog Racks, of which the following is a specification, reference being had therein to the accompanying 10 drawing.

This invention relates to a simple and efficient means for attaching racks to the body of a wagon, and has for its object the production of a simple and efficient attaching 15 device which is formed of sheet metal and which is simple in construction, efficient in operation, and consists of a small number of parts.

Other objects and advantages of the present 20 device will appear throughout the following specification and claim.

In the drawings:—Figure 1 is a transverse section taken through the wagon body showing the rack in position thereon. Fig. 25 2 is a transverse section of a different form of rack applied to the wagon body. Fig. 3 is a perspective view of the socket used in connection with the present invention. Fig. 4 is a perspective view of one of the fingers 30 adapted to be carried by the rack for engaging the socket illustrated in Fig. 3. Fig. 5 is a view of the blank from which the finger illustrated in Fig. 4 is formed. Fig. 6 is a plan view of the blank from which 35 the socket shown in Fig. 3 is formed. Fig. 7 is a detail perspective of the plate which is adapted to be engaged by the lower threaded ends of the socket illustrated in Fig. 3.

40 By referring to the drawings it will be seen that 1 designates the body of the wagon which is provided with the usual side rails 2. These side rails 2 are supported upon the transversely extending beams 3, which 45 beams support the usual flooring 4. A plurality of socket members 5 such as indicated in Fig. 2 are carried by the side rails 2 and constitute a substantially U-shaped bolt portion 6 having lower threaded ends 7 upon which the nuts 8 are threaded for holding the bolt portions in engagement with the rails 2.

50 A circular band 9 is carried by one of the side members of the U-shaped bolt portion 6 and constitutes a socket for receiving

the finger 10. The circular band comprises a pair of substantially semi-circular sections 18, which sections have their respective ends abutting as illustrated in Fig. 3 for producing an efficient socket.

60 The finger 10 comprises a tubular body portion which carries at its upper end a plurality of upwardly extending ears 11 and a plurality of laterally extending ears 12. These upwardly extending ears 11 straddle 65 the vertical portion of the rack 13 and the lower longitudinally extending slat 14 of the rack as illustrated in Fig. 1. The laterally extending ears 12 extend longitudinally of the lower surface of the bottom slat 70 14. The ears 11 are secured to the sides of the rack by any suitable fastening means such as rivets or pins. The laterally extending ears 12 are also secured to the under face of the transverse beam 19 when used as a 75 hay rack by means of pins such as illustrated in Fig. 2 by the numeral 15. The beams 19 support the rails 20 as shown in Fig. 2. The tubular portion of the finger 80 10 is provided with apertures 16 for the purpose of receiving a cotter pin 17, which cotter pin is adapted to fit under the circular band 9 of the socket member 5 and hold the finger 10 in firm engagement with this 85 socket member 5.

85 In Fig. 7 there is shown a perspective view of the plate 22 through which are adapted to pass the threaded lower ends 7 of the bolt portion 6 of the socket member 5. This plate will constitute an efficient 90 bearing means for the nuts which are adapted to be threaded upon the lower threaded portions 7 of the bolt portion 6.

95 It, of course, should be understood that the present device, to wit: the sockets and fingers may be applied to any form of rack for the purpose of facilitating the quick and easy attaching of the rack upon the body of a wagon.

Having thus described the invention what 100 is claimed as new, is:—

A securing device for connecting a rack to the body of a vehicle comprising a socket member provided with a plurality of depending bolt portions, nuts threaded upon the 105 lower ends of said bolt portions for connecting said socket member to said body, said socket member provided with a pair of substantially semi-circular jaws abutting at their adjacent ends and being formed of 110

sheet metal, a finger adapted to fit in said socket, said finger comprising a pair of oppositely disposed parallel upwardly extending ears, a pair of oppositely disposed ears 5 extending laterally of said finger and adapted to engage the under face of a rack, the upwardly extending ears of said finger adapted to engage the sides of the rack, and said ears adapted to receive securing means

for facilitating the attaching of said finger to said rack.

In testimony whereof I hereunto affix my signature in presence of two witnesses.

RAY W. SHELDON.

Witnesses:

GRACE V. JENKINS,
P. P. ADAM.
